UNITED STATES PATENT OFFICE.

GEORGE S. PAINE AND ALTON D. PRIEST, OF WINSLOW, MAINE.

BASKET-HOLDER.

947,024.

Specification of Letters Patent. Patented Jan. 18, 1910.

Application filed March 17, 1909. Serial No. 483,933.

To all whom it may concern:

Be it known that we, GEORGE S. PAINE and ALTON D. PRIEST, both citizens of the United States, and residents of Winslow, 5 in the county of Kennebec and State of Maine, have jointly invented a new and Improved Basket-Holder, of which the following is a full, clear, and exact description.

The purpose of our invention is to provide 10 novel features of construction for a basket holder, particularly adapted for the reliable holding of a plurality of berry baskets or other small fruit baskets at the front of the gatherer, so that berries may be conveniently 15 removed from the plants or bushes and deposited in the baskets, both hands of a person being free for the gathering operation.

The invention consists in the novel construction 20 and combination of parts, as is hereinafter described and defined in the appended claims.

Reference is to be had to the accompanying drawings forming a part of this specification, in which similar characters of reference indicate corresponding parts in all the views.

Figure 1 is a perspective view, showing the construction of the improved basket holder; Fig. 2 is a partly sectional front view of the basket holder and one style of berry baskets shown mounted in position thereon, and both detachably secured by similar novel details, the section being indicated by the broken line 2—2 in Fig. 1; and Fig. 3 is a transverse sectional view of the improved basket holder, and of a differently constructed basket held in place by an engagement therewith of another detail of the 40 invention.

The improved holder may be formed of light, plate metal or other suitable material, one detail thereof consisting of a curved band 5, termed a body plate, that is preferably formed of sheet metal having proper width and length for effective service. The body plate 5 is transversely slotted as at *a*, *a*, near the longitudinal center thereof, these slots being disposed vertically and spaced 45 apart a proper distance. A belt 6 of sufficient length to adapt it to encircle the waist of the wearer of the holder device, is passed through the slots *a*, *a*, so as to connect the belt with the body plate 5, and is provided with a buckle 6^a at one end that enables the 55 wearer to adjust the belt closely about the

waist, so as to hold the body plate at the front of the person.

Two similar bracket arms 7, 7, preferably formed of plate metal and having a flange 60 bent laterally thereon at one end thereof, as shown at *b*, are secured on the front of the body plate at an equal distance each side of the longitudinal center of said plate, by rivets or other means. A flange *c* is bent 65 laterally on the front end of each bracket arm 7, on which flanges a back plate 8 is secured by rivets or other means, thus disposing said back plate across the person when in position for service. From the lower edge 70 of the back plate 8, a preferably plate metal shelf 9, is bent forwardly in a horizontal plane or at right angles to the back plate and having an equal length therewith. For convenience in use, the upper corners of the 75 back plate 8 are rounded and in a like manner the front corners of the shelf 9 are also rounded. As is indicated by dotted lines in Fig. 1, a forward projection *c'* is formed on each flange *c* and extends below the shelf 9, 80 contributing to its support.

An essential feature of the invention consists in the provision of two resilient tongues 10, that are formed or secured on the back plate 8. As is indicated in Fig. 1, the tongues 85 10 project upward from the junction of the back plate 8 with the shelf 9, and are formed integral therewith by slits cutting each tongue loose from the back plate, at each side edge and across the top edge thereof, as 90 shown at *d*. The duplicate tongues may be notched centrally in their upper edges to render them more resilient, and as shown said tongues are spaced apart an equal distance 95 from the longitudinal center of the back plate 8. In or on the shelf 9, two spaced tongues 11 are formed or secured, that project their free end toward the side edges of the shelf and are equally spaced therefrom respectively. In the construction of the holder device shown in Fig. 1, the tongues 11 are formed integrally with the shelf 9 by slitting the material so as to provide free side edges *e* 100 for each tongue, that are connected by transverse slits *e'*.

In use the holder device is adapted to clamp berry baskets of different forms on the shelf or back piece and hold the baskets secured thereon, thus permitting the use of both hands for picking berries that are 110 placed in the baskets.

In Fig. 2, a style of berry baskets A is

shown, that have creviced or slitted bottoms and to secure two baskets in position on the holder, the tongues 11 are raised at their free ends, and said ends are entered in appropriate crevices or slits in the bottoms of said baskets, the latter now being pressed toward each other, which will cause the tongues 11 to bind the baskets upon the shelf and hold them in contact with the back plate 8.

10 Obviously, when the baskets A are filled with berries, they may be removed by sliding them from engagement with the tongues 11 and empty baskets may be placed in position.

15 In Fig. 3, a different style of a berry box or basket B is shown as mounted upon the holder device. The basket B is of a kind having upright side walls and a bottom wall that is spaced at its opposite edges from the side walls, thus affording a crevice between 20 said edges and the side walls. In this case the boxes B are mounted and secured upon the holder device by inserting each tongue 10 on the back plate 8 up through a crevice in the basket that spaces the side edge of the 25 bottom of said box from an adjacent side wall thereof.

It will be seen that upon an insertion of the duplicate tongues 10 up through the crevices mentioned in two boxes such as B, the 30 latter when seated on the shelf 9 will be held securely on said shelf and when filled with berries, may be detached from the back plate by raising the boxes therefrom.

35 For convenience in illustrating and describing the improvement, plate metal has been mentioned as an available material from which to make the same, but we wish to explain that bent wire or other material may also be used in its manufacture and the device be produced therefrom equally as serviceable as if formed of plate metal.

40 Having thus described our invention, we

claim as new and desire to secure by Letters Patent:

1. A basket or box holder, comprising a 45 back plate, a support therefor, a shelf extended forward from the support, and a tongue on the shelf adapted for entering a slit or crevice in the bottom of a basket and securing said basket on the shelf. 50

2. A basket or box holder, embodying a curved body plate, a belt thereon, an upright back plate on the body plate, a shelf extended forward from the back plate, and duplicate tongues on the shelf for detachably 55 securing baskets on the shelf.

3. A basket or box holder, embodying a curved body plate, a belt thereon, an upright back plate carried by the body plate, a shelf extended forwardly from the lower edge of 60 the back plate, and two spaced tongues on the back plate adapted to engage baskets and detachably secure them on the holder.

4. A basket or box holder, embodying a curved body plate, a belt thereon, two spaced 65 bracket arms projected forwardly from the body plate, an upright back plate mounted on the bracket arms, a flat shelf extended forwardly from the lower edge of the back plate and at a right angle thereto, two upwardly extended spaced tongues on the back plate free at their side edges and upper ends, and two similar tongues on the shelf spaced apart and having their free ends projected toward the opposite side edges of the shelf. 70 75

In testimony whereof we have signed our names to this specification in the presence of two subscribing witnesses.

GEORGE S. PAYNE.
ALTON D. PRIEST.
